W. S. HAMM

WINDOW LATCH

Filed April 24, 1926.

Inventor: William S. Hamm
By Gillow, Mann & Co., Attys.

UNITED STATES PATENT OFFICE.

WILLIAM S. HAMM, OF HUBBARD WOODS, ILLINOIS, ASSIGNOR TO THE ADLAKE COMPANY, A CORPORATION OF ILLINOIS.

WINDOW LATCH.

Application filed April 24, 1926. Serial No. 104,285.

The invention relates to an improvement in that type of window latch which forms the subject of my pending application Serial No. 95,892, filed March 19, 1926, the improved 5 latch having some features in common with the one therein disclosed.

The object of the invention is to provide a latch for use in connection with sashes having narrow rails, and is especially intended 10 for application to an upper corner of a drop sash, that is to say, a sash which is opened by being lowered into the wall.

The invention consists in a structure such as is hereinafter described and is illustrated 15 in the accompanying drawings, in which

Fig. 1 is a detail plan, partly in section, of a window with the improved latch applied thereto;

Fig. 2 is a detail elevation of the window, 20 the latch casing being shown in section;

Fig. 3 is a perspective of the latch casing viewed from the inner face thereof;

Fig. 4 is a perspective of the dog-controlling lever;

Fig. 5 is a perspective of the dog; and 25

Fig. 6 is a sectional view of the casing on the line 6—6 of Fig. 3.

The stile of a window casing is shown at 30 10, and is provided with a rack bar 11, with which the dog of the latch cooperates. The top rail of a sash is shown at 12, and its side rail at 13.

The latch casing, generally represented by the numeral 14, is L-shaped and provided 35 with suitable lugs, as 15, 16 and 17, to facilitate its attachment to the sash rails. The casing fits the corner of the sash, one of its legs, as 18, extending horizontally along the top bar or rail 12, and the other leg 19 de- 40 pends along the side rail. The wall of the leg 18 which faces the window casing is aper- 45 tured to accommodate the nose of the dog 20, the heel 21 of which rests against and rocks upon the inner face of the upper end of the leg 19, which is rounded to form a smooth bearing therefor.

An actuating lever 22 is L-shaped and is fulcrumed on the inner face of the end wall of the casing leg 19, which is rounded to pro- 50 vide for it a smooth bearing. The other arm of the lever extends into the leg 18 of the casing and carries a thumb-piece 23 which projects through an aperture in the upper wall thereof. The lever and dog are inter- 55 locked by means of a pair of lugs 24, 25,

formed on the lever adjacent to its angle and between which the dog loosely fits.

A spring 26, reacting between the dog and the wall of the casing, normally holds the nose of the dog in extended or advanced position. A second spring 27 reacts between the lever 22 and a wall of the casing, and normally holds the lever in retracted position. Downward pressure upon the thumb-piece 23 causes the lower end of the lever 22 to rock 60 upon its bearing and to withdraw the dog by the application of pressure through the lug 24, compressing both of the springs. Upon the release of pressure on the thumb-piece both springs operate to restore the latch parts 65 to normal position, advancing the dog and retracting the thumb-piece. Should either of the springs break or become displaced, the other will function to restore the parts to 70 normal position. The lug 25 serves the purpose of retaining the latch elements in proper relation, should the spring 26 fail to act. 75

I claim as my invention—

1. A sash latch comprising an L-shaped casing, the exterior wall at the angle of the 80 casing being internally rounded to form a pivot bearing, one leg of the casing being apertured and at its end being internally rounded to form a pivot bearing, a latching dog rocking upon the first-named bearing 85 and having a latch projection extending through the aperture, a dog-actuating angle lever one end thereof rocking on the second-named bearing and one arm thereof projecting into the other leg of the casing and projecting through a wall thereof, operative connection between the lever and dog, and a spring for advancing the dog. 90

2. A sash latch adapted for attachment to an upper corner of a sash, the depending 95 leg of the latch casing being apertured to accommodate a latching dog and the horizontal leg thereof being apertured to accommodate a thumb-piece, a dog having a rocking bearing at the angle of the casing, an angle 100 lever interlocking with the dog, one end thereof having rocking bearing on the end wall of the depending leg of the casing and the other end thereof carrying a thumb-piece, and a spring for advancing the dog. 105

3. In a sash latch, in combination, a latching dog, a bell-crank shaped controlling lever having pivotal movement about the end of one of its arms and being engageable at its angle with the dog. 110

4. In a sash latch, in combination, an L-shaped casing, a latching dog within the casing, and a bell-crank shaped controlling lever, one arm thereof being pivoted within one section of the casing and the other arm thereof being housed within the other casing section.
5. In a sash latch, in combination, a casing having a chamber adapted to extend paral-

lel with a side margin of a sash, a latching dog housed within the casing, and a bell-crank shaped controlling lever having one of its ends pivoted within the named chamber of the casing and being operatively engaged adjacent to its angle with the dog. 10
15

In testimony whereof I affix my signature.

WILLIAM S. HAMM.
